(57) **CLAIM**

The ornamental design for an orthodontic appliance, as shown and described.

DESCRIPTION

FIG. 1 is a front perspective view of an orthodontic appliance showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top plan view thereof, showing the claim isolated for clarity of view; and,

FIG. 10 is a bottom plan view thereof, showing the claim isolated for clarity of view.

The dashed broken lines in the figures illustrate portions of the orthodontic appliance that form no part of the claimed design.

1 Claim, 10 Drawing Sheets
